DESIGN FOR A CONTROL INSTRUMENT CASING

Frank B. Lambert, Minneapolis, Minn., assignor to Minneapolis-Honeywell Regulator Company,
Minneapolis, Minn., a corporation of Delaware

Application January 9, 1941, Serial No. 97,913

Term of patent 14 years

To all whom it may concern:

Be it known that I, Frank B. Lambert, a citizen of the United States, residing at Minneapolis, in the county of Hennepin and State of Minnesota, have invented a new, original, and ornamental Design for a Control Instrument Casing, of which the following is a specification, reference being had to the accompanying drawing, forming part thereof, and in which

The dominant features of the design are shown in full lines in the drawing.

I claim:

The ornamental design for a control instrument casing, substantially as shown and described.

FRANK B. LAMBERT.
